UNITED STATES PATENT OFFICE.

FREDERICK SCHERR, OF BROOKLYN, NEW YORK.

STEAM-BOILER.

SPECIFICATION forming part of Letters Patent No. 339,478, dated April 6, 1886.

Application filed October 1, 1885. Serial No. 178,735. (No model.)

To all whom it may concern:

Be it known that I, FREDERICK SCHERR, of Brooklyn, Kings county, in the State of New York, have invented a certain new and useful Improvement in Steam-Boilers; and I do hereby declare that the following is a full and exact description thereof.

The improvement relates to the class in which the water and steam are circulated through pipes and the heat is received from the hot products of combustion circulating between.

The improvement relates to the construction of the portions generally termed "headers," being boxes of cast-iron or other suitable material, in which the ends of the tubes are fitted.

The following is a description of what I consider the best means of carrying out the invention.

The accompanying drawings form a part of this specification.

Figure 1 is an outline side elevation showing the general arrangement of the boiler. The remaining figures are on a larger scale and show the novel parts with so much of the ordinary parts as is necessary to indicate their relation thereto. Fig. 2 is a front or face view of two of the headers. Fig. 3 is a plan view of a portion. Fig. 4 is a vertical section on the line *xx* in Fig. 2. Fig. 5 is a vertical section showing a modification.

Similar letters of reference indicate corresponding parts in all the figures where they occur.

A is the drum or separating-vessel, in which the steam is disengaged from the water.

B are the headers, connected, respectively, by liberal passages with the two ends of the drum A. Certain portions of the headers will be designated, when necessary, by additional marks, as B' B''. The inclined tubes C extend through the furnace and constitute the principal heating-surface. I connect the tubes with the headers by the process known as "expanding."

The water moves forward and upward through the tubes C, being partially converted into steam in the passage. The water moves upward through the front series of headers B, backward through the drum A, disengaging from its surface the steam which has been gen-

erated, and descends through the back series of headers B, and again moves forward through the tubes C.

B' is the face or side of the header which connects with the tubes. B'' is the opposite face of the header.

The headers are of cast-iron. They are connected together by bolts P. When it becomes necessary to exchange a tube, certain bolts are removed and the defective tube and the attached headers are taken out. After the new tube is substituted and tightly set in the headers, the headers with their attached tubes are again replaced and the bolts reset. They are provided with hand-holes b, which are of oblong form and secured by oblong covers D, applied on the inside and held in place by bolts E, bridges F, and nuts E'.

B' are the upper and lower faces of the headers. They are finished with conical faces, adapted to match tightly together and to hold themselves reliably in the correct position.

A liberal space is provided for the movement of the water upward and downward through apertures m in the faces B'. These apertures are crossed by spiders M, adapted to be strongly and tightly secured together by bolts P and nuts P'. These may be operated through the hand-holes b when the covers D are removed.

Figs. 2, 3, and 4 show the spiders M as a part of the same casting with the headers and lying in the general plane of the corresponding face B'.

The modification shown in Fig. 5 has the spiders standing farther inward toward the center of the header. This construction will allow the opening m to be unobstructed. In this form the spiders may be either cast in one with the headers or made and applied as separate pieces, as convenience may require.

The hand-holes b need not be of the full size of the tubes C. It has been common heretofore in boilers of this class to make the hand-holes sufficiently large to allow the tubes C to be drawn out and new ones inserted, when required, through these hand-holes; but my construction avoids the necessity for taking tubes out or putting new ones in through the hand-holes.

The hand-holes in my construction only

require to be of such size as to allow an expanding-tool to be inserted to expand the tubes C and effect the necessary strong and tight junction between C and B. The ordinary styles of expanders may be contracted to a size considerably smaller than the tube which they are to set. The hand-holes are only necessary for the setting of the tubes C, and for the introduction at intervals of a 10 cleaning device, as a brush.

The inner face of the side B² adjacent to the hand-hole should be finished so as to make a tight joint with the cover, which, it will be understood, is correspondingly finished near its edge, so that the parts make a tight joint, metal and metal. The oval form of the hand-hole and the corresponding oval form of the cover D allows the cover to be inserted by turning it in a certain position, 15 and by shifting its position, after it is introduced, to be applied on the inner face, so as to tightly close the hole. This has long been a successful mode of closing hand-holes and man-holes in boiler-shells. I have discovered 20 that by giving sufficiently increased dimensions to the headers longitudinally the same construction may be used in headers. There is no objection to the increased length of header—by which I mean the dimensions in 25 30 the direction of the tubes C prolonged.

I make the headers with the ends rounded. There is a plate extending farther to fill out the corners of the rectangle, so that there shall be no considerable aperture between the 35 headers.

When it is necessary to take out a pair of headers and the tubes connecting them, I remove the hand-hole covers of that header, and also of the headers above and below, and 40 take out the bolts P. Then, by slightly springing apart the tubes above and below, which may be effected by a jack-screw or other simple device, I can get the space required to allow for the conicity of the surfaces, and 45 can draw out the tubes with their attached headers.

When the holding-bolts which hold the headers together are arranged to extend through from the steam and water space into 50 the external atmosphere, there is a tendency to leakage along the sides of the bolts. A strong pressure is on the fluid enveloping the head, while air at only ordinary pressure envelops the other end of the bolt. My 55 arrangement avoids the liability to leakage along the bolts, because the bolts sit with both ends immersed in the fluid under pressure.

Modifications may be made in the forms and proportions without departing from the principle or sacrificing the advantages of the 60 invention. The faces B³ may be coned considerably more or less than shown. I prefer that they shall be coned about as shown. The faces B³ may serve if finished plane. It 65 is only essential that they correspond with each other and be finished smoothly, so that they can, by a simple pressure induced by the bolts, be brought into absolutely tight contact.

Although, as above described, it is not necessary to make the hand-holes so large as the tubes, it may be preferable in general practice to give the hand-holes such size. Such 70 will allow the tubes to be taken out and replaced through the hand-holes, if preferred in any case.

I attach importance to the fact that the action of the bolt P is central on the bearing-surfaces, which must be maintained in steam-tight contact around the aperture through which the circulation is effected. By my arrangement the single bolt P connects and disconnects the work, and when in place and properly set up exerts its pressure uniformly 80 on the matched faces.

I claim as my invention—

1. In a sectional steam-boiler, the headers B B, having matched faces and spiders or skeleton cross-frames M and separately removable bolts P, arranged centrally with both ends in the spaces under pressure, as and for 90 the purposes herein specified.

2. In a sectional boiler, the headers B, of elliptical form, casing two tubes each, and 95 having connections, arranged as shown, whereby, when placed together, the tubes will be joggled and the communication between adjacent headers will be in vertical lines, as set forth.

3. The headers B, matched and secured together in joggled vertical series, with communicating passages m, arranged in vertical lines, and having hand-holes with suitable securing means, combined with each other and with 105 securing-bolts P, arranged to allow the headers and tubes to be separately removed and replaced, as set forth.

In testimony whereof I have hereunto set my hand, at Brooklyn, this 16th day of September, 1885, in the presence of two subscribing witnesses.

FRED. SCHERR.
